UNITED STATES PATENT OFFICE.

ELI HENSLEY, OF TULSA, OKLAHOMA, ASSIGNOR OF ONE-HALF TO ELMER WEBB, OF TULSA, OKLAHOMA.

SAFETY HOOK-OFF DEVICE FOR WELLS.

Application filed June 11, 1926. Serial No. 115,347.

The object of this invention is to provide means for connecting and disconnecting the main driving mechanism with the pumping means for individual oil wells, the operation being known as hooking on and hooking off the well while the main power operated devices continue in operation.

A further object is to provide means including a rack element and a plurality of specially mounted pawls, one of which automatically releases the other, so that when the power element is connected, a locking pawl is automatically disengaged for retaining the pumping apparatus of that particular well inoperative.

A further object is to provide, in connection with relatively slideable elements, a plurality of pawls, one of which constitutes an engaging element, and the other a disengaging element, the pawls having the particular relation specified in the operation of the device.

With the foregoing and other objects in view, the invention consists in the novel construction and arrangement of elements described, illustrated and claimed, it being understood that modifications may be made within the scope of the claims, without departing from the spirit of the invention.

In the drawings forming part of this application,

Figure 1 shows the construction in longitudinal section, with parts in elevation, and parts in dotted lines.

Figure 2 is a section on line 2—2 of Figure 1.

Figure 3 is a section on line 3—3 of Figure 1.

Figure 4 is a perspective view of one of the pawls detached from the mounting.

In Figure 1, the power end of the device is at the left, and the pick-up connections are at the right, the hitch rod 10 being connected by means shown conventionally at 11, with tubular element 12 constituting a housing. The pick-up connections shown conventionally at the right, are designated 14, and a rack bar 15 is connected with one of the elements of the pick-up device, in the manner shown at 16, where a head is provided for engagement with element 17.

Assuming that a number of oil wells are to be operated from a centrally located power plant, and the individual pumping apparatus for the several wells are to have

power applied thereto thru hitch rod 10, it will be observed that the tubular element 12 will constantly be in operation, and the object of this device is to provide particular means for coupling bar 15 to tubular element 12, when the individual well is to be placed in operation, and to provide a hook-off device by means of which bar 15 is held in a stationary position while the individual well is not in operation, the retaining means being disengaged automatically when the pawl mounted on an element connected with tubular member 12, is engaged.

Figure 3 shows the construction of a pawl mounting device, comprising a plurality of members 18 and 19 connected by bolts 20, these elements 18 and 19 providing an intermediate chamber or the like designated 20 for receiving the pawls 21.

The pawls 21 each include a cutaway portion 22 providing angular portions 23 and 24 and beveled surfaces for contact with the teeth 27 of rack member 15. The pawls further include knobs or operating devices 28, and each pawl is under the influence of a spring 29 mounted as shown. For convenience the pawl at the left in Figure 1 constituting the hook-on pawl is designated 21 as indicated, and the other pawl constituting the hook-off device, is designated 21', these elements being illustrated in full line and in dotted line position, and the pawl 21 being engaged in Figure 1, the other pawl being disengaged. The mounting device of the right hand pawl, one element of which is designated 19', carries an end member 30 connected with a stationary arm 31 the connection being effected by bolts 32, and when the pawl 21' is engaged with the rack member 15, the latter is held inoperative and the individual well is temporarily disconnected from the main pumping apparatus.

The mounting means for pawl 21 is connected with the housing or tubular element 12, constituting a driving member, in the manner shown at 33, where the end of the driving member 12 is outwardly flared and engages an annular portion 34 in the pawl mounting device.

The draw bar or rack bar 15 carries on the inner end thereof a cylindrical element 15', slideable within tubular element 12 and permitting of the extension of the draw bar in picking up wells. The pawls may be guided in their mounting devices in any suit-

able manner as by ribs 21' operating in grooves in elements 18 and 19.

If the pawls are in the dotted line position of Figure 1, and pawl 28 is then hooked on, the pull toward the left exerted on bar 15, incident to the drive, will release the other pawl on account of the direction in which the teeth engage, and this pawl 21' is then freed by its spring 29'. (The pull on bar 15, toward the right, due to the weight of the apparatus in the well, held pawl 21' in operative position when there was no thrust being imparted thru tubular member 12.)

Having thus described the invention, what is claimed is:

1. A device of the class described, comprising relatively slidable elements, one of which is provided with teeth, pawl mounting devices having longitudinal openings receiving respectively the elements first named, pawls within the mounting devices being connected therewith, one of the mounting devices being connected with one of said elements first named, the pawls being adapted to en-

gage the teeth of the other of said elements, 25 and one of the pawls when engaged acting thru the element having teeth thereon to release the other pawl.

2. A device of the class described, comprising relatively slidable elements, one of which is provided with teeth, means for connecting the other element with power operated mechanism, means for connecting the toothed element with pumping devices, pawl mounting devices having longitudinal openings receiving respectively the elements first named, pawls within the mounting devices and connected therewith, one of the mounting devices being connected with one of the elements first named, the pawls being adapted 40 to engage the teeth of the other of said elements, and one of the pawls when engaged acting thru the toothed element to release the other pawl.

In testimony whereof I affix my signature.

ELI HENSLEY.
